UNITED STATES PATENT OFFICE

JOHN LOGIE BAIRD, OF LONDON, ENGLAND, ASSIGNOR TO TELEVISION LIMITED, OF LONDON, ENGLAND, A BRITISH COMPANY

TELEVISION OR LIKE SYSTEM AND APPARATUS

Application filed April 8, 1929, Serial No. 353,636, and in Great Britain May 15, 1928.

This invention concerns improvements in or relating to television or like systems and apparatus which are used for the transmission to a distance of a reproduction of an object, view, or scene hereinafter referred to as a picture.

The invention relates to that type of the above apparatus wherein there is employed a device (for example a rotating disc with a spiral arrangement of holes, lenses, or other light-apertures) which effects exploration, in a series of parallel bands. With such a device, one dimension of the area of the object or picture explored is determined by the number of the bands which are used in the exploration.

Where the picture to be produced is oblong in form it is sometimes advantageous to view it with the longer side of the oblong horizontal and sometimes advantageous to view it with the longer side vertical. That is to say, certain pictures are best obtained in a reproduction the side of which is long and the height relatively short, other pictures with the height great and the width relatively small.

According to the present invention means are provided in the transmitter and receiver whereby the same machine can view or show the picture in either form.

The invention comprises the provision, in television or like apparatus comprising an exploring device having a series of light-apertures which effects exploration in a series of parallel bands, of means for adjusting the orientation of those bands for the purpose above referred to.

In such apparatus wherein the exploring device is constituted by a rotating disc provided with a spiral arrangement of light-apertures, adjustment of the orientation of the bands may be obtained by rendering the light-apertures effective, as regards their exploring function, at different points of their path of travel. For example, the arrangement may be such that exploration is effected at a part of the apparatus where the light-apertures are travelling substantially vertically, or at a part where the light-apertures are travelling substantially horizontally.

In the former case, the exploration is suitable for a picture of greater height than width while in the latter case it is suitable for a picture of greater width than height.

Convenient constructions of apparatus that come within the scope of the present invention will now be described by way of example and by the aid of the accompanying diagrammatic drawings, in which—

Figures 1, 2 and 3 illustrate different forms of receiving apparatus; and

Figures 4, 5, 6 and 7 different forms of transmitting apparatus.

In Figure 1 the receiving apparatus comprises an exploring disc 2 having the usual spiral arrangement of holes, mirrors, lenses or other light-apertures indicated at 4. In the front part 6 of the casing of the apparatus are formed two viewing apertures 8 and 10 behind each of which and behind the disc 2 is located, respectively, a glow lamp or other light-screen 12, 14. Current modulated by the picture signals from the transmitting station is fed through terminals 16 and conductors 18, 20 to either of the lamps 12, 14 according to the setting of a switch 22. With this apparatus, if the picture to be received has its vertical dimension longer than its horizontal dimension, it will be viewed through the aperture 8 at the side of the disc 2, the switch 22 being so set that the lamp 12 is illuminated; while if the vertical dimension of the picture is less than the horizontal dimension, the aperture 10 at the top of the disc 2 will be employed, the switch 22 being set to illuminate the lamp 14.

In Figure 2 a single viewing aperture 24 is formed in a part 26 of the front of the casing of the receiving apparatus. This part 26 is supported by a shaft 28 rotatable in bearings 30 secured to the casing and arranged in line with the shaft of the exploring disc 2. A lamp 32 is mounted upon an arm 34 rotatable on a bearing sleeve 36 for the shaft of the exploring disc 2. To rotate the part 26 in company with the arm 34 there is mounted, in a bearing 38 in the casing, a counter shaft 40 carrying sprocket wheels 42 which are coupled, respectively, by driving bands 44 with sprocket wheels 46, one on the

shaft 28 and the other on the hub of the arm 34. The shaft 40 has a hand-wheel 48 by which it may be turned. In the use of this apparatus, when the picture has its greater dimension disposed horizontally, the part 26 and the lamp 32 will be adjusted by turning the countershaft 40 to bring the viewing aperture 24 and the lamp 32 to the top of the disc 2, as shown in Figure 2. On the other hand, if the longer dimension of the picture is vertically disposed, the part 26 and the lamp 32 will be adjusted by the hand-wheel 48 to bring the aperture 24 and the lamp 32 to the side of the disc 2. The construction of Figure 2, is also useful in framing the picture as small inaccuracies in framing can be rectified by adjusting, by means of the hand-wheel 48, the position of the aperture 24 and the lamp 32. The picture signals are fed to the lamp 32 by conductors 50 which may be flexible leads connected with terminals (not shown) supported on the casing of the apparatus.

The receiving apparatus of Figure 3 has a single viewing aperture 52, placed opposite the lamp 54 to which the picture signals are fed by way of terminals 56, the exploring disc 2 being located, as in the constructions of Figures 1 and 2, between the aperture 52 and lamp 54. As shown in Figure 3, the apparatus is adapted for the viewing of an oblong picture which has its greater dimension disposed vertically. When a picture having its greater dimension disposed horizontally is to be viewed, the apparatus is turned through a right angle so that it rests upon what previously was its side 58. This adjustment brings the aperture 52 to the top of the exploring disc and, of course, turns the aperture through a right angle making it suitable for the picture to be viewed.

Adjustments corresponding to the above will be made at the transmitting station.

A transmitting apparatus akin in construction to the receiver of Figure 1 is shown, in Figure 4, in which the front part 7 of the apparatus has formed in it two framing apertures 9 and 11, behind each of which, respectively, is a light-sensitive cell 13, 15. An exploring disc 3 extending between the apertures and cells has the usual spiral arrangement of light-apertures which are indicated at 5. Current modulated by the cells is fed to the amplifying or transmitting part of the apparatus by conductors 19, 21 and terminals 17, a switch 23 being set according to which of the cells 13, 15 is in use, it being understood that the cell 13 will be in circuit for the transmission of a vertically-disposed oblong picture and cell 15 for an oblong picture which is horizontally disposed. The object of which an image is to be transmitted will be situated in front of the apparatus and on or about on the line passing through the

centres of the cell 13 and aperture 9 or the cell 15 and aperture 11, as the case may be.

A transmitting apparatus of the type wherein the object is explored by a light spot is indicated in Figure 5. In this apparatus there are two projecting lamps 60, 62, the lamp 60 being so situated in relation to the disc 3 that the object 64 will be explored by the light-apertures 5 when these are at the top of the disc 3, a position suitable for the transmission of an oblong picture whose greater dimension is horizontally disposed. The lamp 62 is arranged so that the object 64 is explored by the light-apertures when on the side of the disc, this arrangement dealing with the transmission of an oblong picture that is vertically disposed. If the lamps 60, 62 are electric lamps, suitable switching gear may be provided so that either of them may be in action to the exclusion of the other. Or, alternatively, a single lamp may be employed and provision made for shifting it as occasion arises from one to the other of the two positions occupied by the lamps 60, 62 in Figure 5.

Figure 6 shows a transmitting apparatus having provision for adjustment of the same kind as that of the receiver of Figure 2. In Figure 6 the object 64 is explored by an exploring disc 3 and a light-sensitive cell 33, through a framing aperture 25 in a partition 27. This partition is mounted upon a shaft 29 supported in a fixed bearing 31 in line with the shaft of the disc 3, the shaft 29 carrying also an arm 35 upon which the cell 33 is supported, conductors 51 leading the current modulated by the cell 33 to the amplifier or other part of the transmitting apparatus.

In this construction the shaft 29 is turned by a hand-wheel 49 to bring the cell 33 and aperture 25 to the top or the side of the disc to deal with an oblong picture whose greater dimension is disposed, respectively, horizontally or vertically. Obviously, small "framing" adjustments may also be made by turning the hand-wheel 49, as in the construction of Figure 2.

Figure 7 illustrates a transmitting apparatus of the same general construction as the receiver of Figure 3. This transmitter comprises a casing the front part of which has a single framing aperture 53. Behind this aperture 53 there is a light-sensitive cell 55 which is electrically connected with terminals 57 from which current modulated by the cell 55 is led to the transmitting part of the apparatus. The object, of which an image is to be transmitted, will be located on or about on the line passing through the centres of the aperture 53 and cell 55 and will be explored by the light-aperture 5 of the disc 3 which extends between it and the aperture 53 and cell 55. As in the construction of Figure 3, the apparatus will be turned so as to rest on the part 59 which is its side in Figure 7 when

an oblong picture is to be transmitted the longer dimension of which is horizontally disposed. As shown in Figure 7, the position of the apparatus is suitable for an oblong picture which has its greater dimension vertical.

5 I claim:—

1. In apparatus for use in transmitting light images, the combination with an exploring device, of an opaque screen disposed adjacent said device, spaced portions of said screen being constructed to permit passage of light through the same and through said exploring device to frame the image, means for associating electrical and light impulses, and means for rendering said last named means operative adjacent one only of said spaced portions on the screen.
- 15 2. In apparatus for use in transmitting light images, the combination with a rotatable exploring device, of an opaque screen co-operating with said device, said screen having framing apertures spaced about the exploring device, a plurality of elements for associating electrical and light impulses, one of said elements being operatively related to each aperture, and means for rendering any one of said elements operative to orientate the image.
- 20 3. In apparatus for use in transmitting light images, the combination with a rotatable exploring device, of an opaque screen cooperating with said device, said screen having framing apertures spaced about the exploring device, a plurality of elements for associating electrical and light impulses, one of said elements being operatively related to each aperture, an electrical circuit, and means for selectively including one of said elements in the circuit to orientate the image.
- 25 40

In testimony whereof I affix my signature.
JOHN LOGIE BAIRD.
